DESIGN FOR A DRINKING CUP

Harry G. Klassen, Chicago, Ill.

Application August 26, 1942, Serial No. 108,040

Term of patent 14 years

To all whom it may concern:

Be it known that I, Harry G. Klassen, a citizen of the United States, residing at Chicago, in the county of Cook and State of Illinois, have invented a new, original, and ornamental Design for a Drinking Cup, of which the following is a specification, reference being had to the accompanying drawing, forming part thereof,

Fig. 1 is a side elevational view of a drinking cup, showing my new design;

Fig. 2 is a top plan view; and

Fig. 3 is a bottom plan view thereof.

I claim:

The ornamental design for a drinking cup, as shown,

HARRY G. KLASSEN,
